[57] CLAIM

The ornamental design for a hanger, as shown and described.

DESCRIPTION

FIG. 1 is a front elevational view of a hanger showing our new design, the rear elevational view being a mirror image; FIG. 2 is a left side elevational view thereof; FIG. 3 is a right side elevational view thereof; FIG. 4 is a top plan view thereof; FIG. 5 is a bottom plan view thereof;

FIG. 6 is a front elevational view of an alternate embodiment of FIG. 1, the rear elevational view being a mirror image; FIG. 7 is a top plan view of FIG. 6; and, FIG. 8 is a bottom plan view of FIG. 6.

The undisclosed left and right side elevational views of FIG. 6 are identical to FIGS. 2 and 3 respectively.
